UNITED STATES PATENT OFFICE.

JOHN J. REINHOLD, OF MARIETTA, PENNSYLVANIA.

INDICATING DEVICE FOR TYPEWRITERS.

Application filed March 10, 1923. Serial No. 624,160.

To all whom it may concern:

Be it known that I, JOHN J. REINHOLD, a citizen of the United States, and a resident of Marietta, county of Lancaster, State 5 of Pennsylvania, have invented certain new and useful Improvements in Indicating Devices for Typewriters, of which the following is a specification.

This invention relates to an indicating 10 device for typewriters.

The object of this invention is to eliminate the uncertainty of when the end of the sheet is about to appear at the point where the writing is produced, or more particularly, to provide a device which will indicate how much of the paper remains for further writing, especially when the end of the paper has passed around the platen to a point where it cannot be seen.

20 This invention resides in the particular construction and combination of parts which will be fully understood from the following description, taken in connection with the accompanying drawing, forming 25 a part hereof, and in which similar numerals refer to similar parts throughout the several views.

Fig. 1, is an end view of a portion of a typewriter, and shows one form of my invention attached thereto.

Fig. 2, is a plan view of Fig. 1.

In the construction represented in the drawing, the bracket 6 is fixed to the side frame 7 of the carriage through the screws 35 8 and 9. A threaded shaft 15 is carried by the bracket 6 and adapted to rotate on the journals 10 and 11. A spiral gear 12 is fixed to the platen shaft 5 and adapted to mesh with the threads 14 of the shaft 40 15. It is apparent that if the platen 16 is caused to rotate, the gear 12 will cause the threaded shaft 15 to rotate.

The bracket 6 is provided with a slot 17 which guides the carriage 18 to move lengthwise relative to the shaft 15. The carriage 45 18 carries a pointer 19 and a casing 20. A key pin 21 is adapted to slide vertically in the casing 20, and the end 22 thereof to engage with the threads 14. The spring 23 50 is adapted to normally hold the key pin 21 in engagement with the threads 14.

55 It is apparent that when the shaft 15 rotates the carriage 18 and the parts carried thereby will move lengthwise relative to the shaft 15.

The head 4 forms part of the key pin

21, and provides a convenient means whereby the end 22 of the key pin may be disengaged with the threads 14, this being accomplished by pulling the key pin up 60 against the action of the spring 23. When the end 22 of the key pin is disengaged with the threads 14, the carriage 18 including the parts carried thereby, may be moved lengthwise relative to the shaft 15, and independent of any rotating movement of the shaft 15.

The paper guide 24 is graduated as shown at 25; said graduations being adapted to correspond with the graduations shown at 70 26 on the bracket 6. In this particular case these graduations are adapted to indicate inches of paper, or in other words, the distance from the graduation around the platen to the point where the writing is produced. 75

To avoid any jamming of the carriage 18 against the bracket 6 at the end of its travel, the shaft 15 is devoid of threads for a certain distance, as shown at 27 and 28; therefore the end 22 of the key pin becomes disengaged with the threads 14 when the carriage 18 reaches the extreme points, and movement of the carriage 18 through the action of the thread 14 thereby ceases.

The manipulation of this device is as follows:—The paper is placed in the typewriter in the usual manner, and writing is carried on until the end thereof reaches a point somewhere within the limits of the graduations 25 on the paper guide. About 90 this time it is usual that the typist is concerned as to how much paper remains for further writing. This is indicated in inches by the graduations 25; for instance, suppose the end of the paper coincides with the 95 graduation $3\frac{3}{4}$, indicated on the drawing by the letter (a), this indicates that there is $3\frac{3}{4}$ inches of paper remaining for further writing.

Now the key pin 21 is disengaged with the threads 14 and the carriage 18 is moved in the slot 17 until the pointer 19 coincides with the graduation $3\frac{3}{4}$ on the scale 26; here the key pin 21 is again engaged with the threads 14. Writing should now be 100 continued and the typist may at any time note how much paper remains for further writing by observing the location of the pointer 19; for as the platen 16 rotates to feed the paper forward, the pointer 19 105 moves along the scale 26 at the same rate the paper moves around the platen; and 110

when the pointer 19 reaches zero on the scale 26, the end of the paper is at the point where the writing is produced.

It is obvious of course that the graduations 25 and 26 might be adapted to indicate number of lines instead of inches of paper; or there may be other modifications in the form of graduations employed.

In the drawing I have shown the spiral gear 12 of substantially the same diameter as the platen 16, consequently the pointer 19 will move the same distance as the paper moves when rotating the platen; however I prefer in actual practice to make said spiral gear smaller than the platen and accordingly reduce the size of all other new parts involved in the construction of this device; then the pointer 19 will not move as great a distance as the paper moves, but the graduations 26 may then be spaced and marked to indicate the actual movement of the paper. While such reduction in size is not necessary to the successful operation of this device, it seems that it provides a device which would be considered as more appropriate as a typewriter fixture.

Having thus described my invention, what I claim and desire to secure by Letters Patent is as follows:

30 1. In a printing machine, the combination with a platen adapted to feed a sheet of paper to the printing elements, of a scale adapted to coact with the end of said paper and indicate the distance from said end to 35 the point where the printing is produced,

a gear adapted to rotate through movement of said platen, a threaded shaft adapted to rotate through rotating movement of said gear, a second scale, the graduations of which corresponds with the 40 graduations of the first said scale, and a pointer adapted to move along said second scale through rotating movement of said threaded shaft, the movement of said pointer relative to said second scale being adapted to correspond with the movement of the 45 end of said paper relative to the first said scale.

2. In an indicating device comprising a platen, a spiral gear fixed to said platen and adapted to rotate therewith, a threaded shaft adapted to mesh with said spiral gear and rotate through rotating movement of the gear, a scale, and a pointer adapted to move along said scale through rotating 55 movement of said threaded shaft.

3. In an indicating device comprising a platen, a spiral gear fixed to said platen and adapted to rotate therewith, a threaded shaft adapted to mesh with said spiral gear 60 and rotate through rotating movement of the gear, a scale, a pointer adapted to move along said scale through rotating movement of said threaded shaft, and means for arresting the movement of said pointer at the 65 end of said scale.

In testimony whereof I affix my signature.

JOHN J. REINHOLD.
